UNITED STATES PATENT OFFICE.

CHARLES PHILO MOSHER, OF GROTON, NEW YORK, ASSIGNOR TO CORONA TYPEWRITER COMPANY, INC., A CORPORATION OF NEW YORK.

TYPE-WRITING MACHINE.

1,269,203.

Specification of Letters Patent. Patented June 11, 1918.

Original application filed October 16, 1915, Serial No. 56,242. Divided and this application filed December 20, 1915. Serial No. 67,812.

To all whom it may concern:

Be it known that I, CHARLES PHILO MOSHER, a citizen of the United States, and a resident of Groton, county of Tompkins, 5 and State of New York, have invented certain new and useful Improvements in Type-Writing Machines, of which the following is a full, clear, and exact description.

This invention relates more particularly 10 to the ribbon mechanism of foldable visible or front-strike typewriting machines in which the keys of the keyboard may be brought into close relation to the platen to make the machine compact when not in use, 15 and is a division of my application Serial No. 56,242, filed October 16th, 1915.

One of the principal objects of the invention is to provide a typewriting machine in which a universal or standard keyboard may 20 be employed and in which the ribbon mechanism may be operated by the keys of the keyboard and the entire keyboard and key action folded with respect to the platen and ribbon mechanism to place the keys in compact relation to the platen without disturbing the coöperative relation between the 25 keys and the ribbon mechanism.

Another object of the invention is to provide a foldable support on which is mounted 30 the type-bars and a universal or standard keyboard having individual keys for operating individual type and wherein the pivotal part of the foldable support may serve as a connecting means between the keys and the 35 ribbon mechanism for the platen carriage in order that no break or disconnection is necessary whether the machine is in a folded position or in an unfolded position.

A further object of the invention is to 40 provide a simple and efficient mechanism for vibrating a ribbon to cover and uncover the printing point and for imparting a step-by-step lengthwise movement to the ribbon.

A still further object of the invention is 45 to provide simple and efficient connecting means between the ribbon mechanism and the keys of the keyboard of a foldable typewriter.

A still further object of the invention is 50 to provide a typewriting machine in which the ribbon mechanism and the parts operat-

ing the same are of simple construction and may be readily made and assembled.

With these and other objects in view, the invention will be hereinafter more particularly described, with reference to the accompanying drawings, which form a part of this application, and will then be pointed out in the claims at the end of the description.

In the drawings, Figure 1 is a longitudinal section of one form of machine embodying the invention, showing a construction wherein the entire mechanism of the machine may be inclosed within the carrying case which may form a frame or support 60 for the typewriter mechanism.

Fig. 2 is a vertical transverse section taken on the line II—II of Fig. 1, the type-bars and parts of the key action being removed to illustrate in a better way the ribbon mechanism.

Fig. 3 is a vertical longitudinal section, partly in elevation, showing the machine in a folded compact condition.

Fig. 4 is a fragmentary sectional plan, 75 showing the operating means for the ribbon vibrator and the lengthwise feed of the ribbon mechanism.

Fig. 5 is a fragmentary section of a part of the connecting mechanism between the foldable parts of the typewriter, showing how the ribbon mechanism may be operated from the keys without any disconnection whatever between the universal bar and the ribbon mechanism.

Fig. 6 is a vertical section taken on the line VI—VI of Fig. 2 of a part of the ribbon operating mechanism; and

Fig. 7 is a fragmentary side elevation of a part of the mechanism for moving the ribbon lengthwise transversely of the machine.

While the invention is shown as applied to a typewriter in which an inclosing case is employed, it will be understood that the folding principle between the key-operated levers and the ribbon mechanism may be embodied in a machine in which an ordinary or any preferred form of frame may be employed or a frame independent of such case, and that said foldable principle as well as the construction of the ribbon and

operating means therefor may be employed in typewriters of various constructions.

The casing 10 has a main member 11 and a top member or cover 12 which is hinged at 13 to said main member 11. At the forward lower edge of the main member 11 is a foldable member 14 which is pivoted or hinged at 15 to said main member 11 so that said member 14 may be folded upwardly 10 and when so folded and the cover 12 thereon moved over and forward as shown in Fig. 3, a substantially uniform and regular inclosing case is provided. This member 14 may be held in its open position by means 15 of stays 16 or any other suitable means, and said stays may be slotted as at 17 to engage headed pins or studs 18. The stays are normally forced in one direction by springs 19 and the slots 17 are curved or so arranged 20 that in one position the stays will act as a lock, and when forced against the springs 19 the case member 14 may be moved to its folded position.

A foldable support or member 20 is pivotally held to a transversely extending rod 21 which is supported in the sides of the main casing member 11 or in sleeves which serve as the direct bearing for the support 20 and at its forward end said foldable support 20 may be connected by links 22 to the member 14 so that the member or support 20 may be folded with the member 14 of the case. The support 20 has sides 23 which may be connected by a transverse bar 24 and 35 mounted in said support 20 is a segment 25. Type-bars 26 are pivoted to the segment in any suitable way, as to a rod 27, and said type-bars are adapted to carry a plurality of type and be supported at their outer ends 40 on a cushion 28, the latter being held to a cushion supporting frame 29 extending outwardly from and supported by the segment. The type-bars are each normally forced in one direction by springs 30 and are each 45 connected by a link 31 to one arm of a bell-crank lever 32. Each bell-crank lever is pivotally held to a rod or support 33. There are four rods each being adapted to support a plurality of the levers 32. The bell-50 crank levers 32 each have one arm, as 34, provided with a cam edge 34^a which is adapted to engage a cam edge 35 of key-operated levers 36. These key-operated levers 36 are supported in groups or banks upon 55 rods or supports 37 which are horizontally arranged in the normal operative position of the machine under the rods 33 and correspond in number to said rods 33. As each key is depressed the cam edge 35 will operate 60 its coöperating bell-crank lever and through a link 31 will move the type bar upwardly and rearward for printing purposes, and by reason of the arrangement in groups or banks a substantially uniform touch is obtained.

The platen carriage 38 may be of the usual or of any preferred form. As shown it comprises a rear guide or base 39, the upper and lower edges of which are each provided with a raceway which is opposed to the raceway or track of transversely extending bars or members 40 and 41, both of which may be secured to a strengthening plate or member 42 held to the rear plate or wall of the main casing member 11. Balls 75 or other anti-friction devices 43 are arranged in the raceways to adapt the bed and carriage to travel easily transversely of the machine. The carriage may have end plates 44 in which is mounted to rotate the usual 80 platen or roll 45. The carriage may have the usual paper apron 46 and the usual finger knobs 47 for rotating the platen, and may also be provided with the usual or any preferred form of line-spacing means, paper 85 fingers and other attachments usually employed in typewriting machines, but as such features form no part of the present invention it is thought unnecessary to describe or show them in detail. 90

To vibrate the ribbon and to move the same lengthwise of the platen in a foldable typewriting machine it is necessary that provision be made whereby the folding principle involved will permit the operation of such ribbon mechanism by the depression of the keys during the printing operation. As one means, I provide a universal bar 48 which is suspended by arms 49, the latter being pivotally held at 50 on the type-bar 100 segment 25, there being any suitable number of arms 49 or other supports for the bar 48. The universal bar 48 is adapted to be engaged by the rear cam edge 51 of the type-bars 26. The purpose of the cam edge 51 of the type-bars is to start the universal bar gradually during the upward and rearward movement of the bars and to give the universal bar an accelerated movement without altering the uniform character of the touch of the keys and in order that no sudden jar on the keys may be apparent to the operator when the type-bars start to actuate said universal bar. At the rear of the universal bar are upwardly extending arms 105 116 115 120 125 130 135 140 145 150 155 160 165 170 175 180 185 190 195 200 205 210 215 220 225 230 235 240 245 250 255 260 265 270 275 10185 10190 10195 10200

The rod 21, Figs. 2 and 5, has a cam member 57 secured thereto near one end thereof adjacent to the outer surface of one of the sides of the support 20, and this cam member 5 is adapted to engage a slidable co-operating cam member 58. The cam member 57 has a substantially V-shaped portion 59 or a plurality of cam portions if preferred fitting a correspondingly shaped recess or recesses in the slidable non-rotating cam member 58, the latter being slidably held by a key or otherwise to a fixed sleeve 60 through which one end of the rod 21 passes, said cam member 58 being normally forced inwardly by means of a spring 61. The sliding cam member 58 is provided with an annular groove which is engaged by the forked end 62 of a lever 63. The lever 63 is substantially bell-crank shaped and is pivoted at 64 to a lug on one of the sides of the main casing member 11 and has its upper arm 65 extending inwardly and provided with a slotted or forked end 66 which is adapted to engage a pin 67 extending outward from a rod 68, so that on each movement of the lever 63 as will be presently described, the said rod 68 by means of the pin 67 will be rocked on its pivot pins or screws located at the ends thereof.

30 The rod or shaft 68 serves as the direct operating or connecting means for the vibrating mechanism for the ribbon to move the latter to cover and uncover the printing point, and as a means whereby mechanism 35 may be operated to give the ribbon a step-by-step movement lengthwise in the direction of movement of the platen, the ribbon mechanism if desired being constructed to adapt the ribbon to have a plurality of fields 40 or zones of different colors, or to remain inactive for stenciling purposes. As shown, the rod or shaft 68 has an arm 69 projecting outward therefrom which is connected to one end of a link 70. The link 70 is connected to an outwardly extending arm 71 which is pivoted at 72 to a bracket 73, the latter having downwardly extending arms secured to the plate 41 forming a part of the carriage track. The arm 71 forms a 45 part of a ribbon vibrator and at a portion thereof may have outwardly extending spaced lips or parts 74 forming a type guide or aliner. A plate 75 may be secured to or formed integral with the arm 71 and this plate forms a ribbon holder through which the ribbon 76 is threaded. The plate or holder 75 has openings 77 and is provided with spaced parts 78 forming suitable guides for the ribbon on opposite sides of the printing point, said parts 78 being spaced apart far enough to permit the type to print against the platen. As the rod 68 is rotated or oscillated by the mechanism already described, the arm 69 will move the link 70 60 and through the latter vibrate the ribbon

holder 75 and aliner 74, thereby causing the ribbon to cover and uncover the printing point as each key is operated.

The ribbon extends beyond the sides of the ribbon vibrator and may be guided in the ends 79 of the brackets 80, said ends having slots 81 for the ribbon to pass through. The ends of the ribbon are passed about spools 82 and 82^a. These spools are mounted to rotate on a fixed part of the 75 casing and are adapted to be readily removed to permit a new ribbon to replace an old one. The ribbon spools may each be provided with a ratchet or toothed portion or member 83 formed on the spool or separate therefrom as preferred, and adapted to engage the teeth of each member is a pawl or dog 84. Each pawl 84 is pivotally held at one end to an arm 85, the latter being held to the rod or shaft 68, a spring 86 85 being arranged on each of said arms adapted normally to force the pawl to an engaging position. The arms 85 are adapted to slide along the rod 68 and said arms for both spools are connected by a transversely 90 extending bar or element 87 having one or more substantially V-shaped projecting portions 88 adapted to engage notches 89 in said rod 68. The arms 85 are so positioned that only one pawl is engaged with the teeth of 95 the toothed member of one of the spools at a time so that by shifting the bar 87 lengthwise of the rod or shaft 68 one pawl is disengaged from its co-operating spool toothed member 83 while the other is made to engage 100 its co-operating spool member, thus the ribbon may be made to travel toward either side of the machine with a step-by-step movement. The rod 68 is thus operated through the lever 63 and its connection with 105 the key action as previously described and by the rocking movement of said rod or shaft 68 the ribbon is moved lengthwise and also vibrated to cover or uncover the printing point as shown in full lines in Fig. 1. 110

Any suitable means may be employed as an escapement mechanism for letter-spacing the carriage. As shown the carriage has a rack 90 secured to the base 39, and engaging this rack is a pinion 91, said carriage being 115 attached to a flexible connection 92 which passes about a spring drum 93 tending normally to force the carriage transversely of the machine. The pinion 91 is held to a ratchet wheel 93, and the teeth of this ratchet 120 wheel are engaged by a pawl 94 carried by a toothed wheel 95, said pawl permitting the carriage to be moved freely in one direction. The toothed wheel 95 is engaged by the usual loose or limber dog 96 and a fixed dog 97, 125 said dogs being held to the rod 68 so that when said rod is operated by the depression of any of the key-operated levers 36, as previously described, the dogs will be moved to permit the toothed wheel 95 to escape and 130

4. *It is an object of the present invention to provide a means for* 1,269,203
thereby permit the carriage to move a letter space at each depression of a key-operated lever 36 in the usual way, it being understood that the escapement may be operated 5 through a source independent of the means employed for operating the ribbon vibratory and lengthwise feeding means.

universal bar to the ribbon mechanism to adapt said mechanism to be operated each time a key-operated lever is depressed and which permits the keys of the keyboard to be moved into compact relation to the platen carriage. 70

3. In a visible typewriting machine, the combination of a platen carriage, type bay-

From the foregoing it will be evident that a simple and compact typewriter is provided whereby the entire key action including the type-bars, space-bar, shift mechanism and universal bar are adapted to fold without destroying the co-operative relation between the key action and the ribbon mechanism; that all of the mechanism is adapted to be inclosed within a case so as to be entirely protected; that the ribbon mechanism is always maintained in its proper co-operative relation to the platen carriage; that the foldable principle disclosed herein permits a universal or standard keyboard to be employed in which a single case shift may be used; and that simple and efficient ribbon mechanism is provided which may be readily made and assembled.

Having thus described my invention, I claim as new and desire to secure by Letters Patent:

1. In a visible typewriting machine, the combination of a platen carriage, type-bars having an upward and rearward movement, key-operated levers forming a part of a universal keyboard and operatively connected to the type-bars, a foldable support on which the type-bars and key-operated levers are mounted and which partake of the foldable movement of said support, a universal bar movably held upon said foldable support, ribbon mechanism normally maintained in a fixed relation to the platen carriage and adapted to move the ribbon lengthwise of the carriage and to vibrate the ribbon to cover and uncover the printing point, and means operatively connecting the universal bar to the ribbon mechanism to adapt said mechanism to be operated each time a key-operated lever is depressed and which permits the keys of the keyboard to be moved into close relation to the platen carriage and the co-operative relation between the universal bar and the ribbon mechanism maintained.

2. In a typewriting machine, the combination of a platen carriage, type-bars, key-operated levers forming a part of a universal keyboard and operatively connected to the type-bars, a foldable support on which the type-bars and key-operated levers are mounted and which partake of the foldable movement of said support, a universal bar movably held upon said foldable support, ribbon mechanism normally maintained in a fixed relation to the platen carriage, and foldable means operatively connecting the

universal bar to the ribbon mechanism to 65
adapt said mechanism to be operated each
time a key-operated lever is depressed and
which permits the keys of the keyboard to
be moved into compact relation to the platen
carriage. 70

3. In a visible typewriting machine, the combination of a platen carriage, type having an upward and rearward movement, key-operated levers forming a part of a universal keyboard and operatively connected to the type, a foldable support on which the type and key-operated levers are mounted and which partake of the foldable movement of said support, a universal bar, ribbon mechanism, and foldable means operatively connecting the universal bar to the ribbon mechanism to adapt said mechanism to be operated each time a key-operated lever is depressed and which permits the keys of the keyboard to be moved into vertical compact relation to the platen carriage and the cooperative relation between the universal bar and the ribbon mechanism maintained without disconnection. 75 80 85

4. In a typewriting machine, the combination of a platen carriage, type, key-operated levers forming a part of a universal keyboard and operatively connected to the type, a foldable support on which the key-operated levers are mounted and which partake of the foldable movement of said support, a universal bar, means for vibrating a ribbon and for imparting a lengthwise feed thereto, and foldable means operatively connecting the universal bar to the ribbon operating means. 90 95 100

5. In a visible typewriting machine, the combination of a platen carriage, type-bars having an upward and rearward movement, key-operated levers forming a part of a universal keyboard and operatively connected to the type-bars, a foldable support on which the key-operated levers are mounted and which partake of the foldable movement of said support, a universal bar, ribbon mechanism, and foldable means operatively connecting the universal bar to the ribbon mechanism to adapt said mechanism to be operated each time a key-operated lever is depressed and which permits the keys of the keyboard to be moved into compact relation to the platen carriage and the co-operative relation between the universal bar and the ribbon mechanism maintained.

6. In a visible typewriting machine, the combination of a platen carriage, type-bars, key-operated levers forming a part of a universal keyboard and operatively connected to the type-bars, an upwardly foldable support on which the type-bars and key-operated levers are mounted and which partake of the foldable movement of said support, a universal bar, ribbon vibrating mech-

anism, mechanism for feeding the ribbon lengthwise, and foldable means to adapt the ribbon vibrating and feeding mechanisms to be operated each time a key-operated lever 5 is depressed and which permits the keys of the keyboard to be moved into compact relation to the platen carriage and the coöperative relation between the universal bar and the said mechanisms maintained.

10 7. In a visible typewriting machine, the combination of supporting means, a platen carriage movable along said supporting means, a foldable support movable relatively with respect to said supporting means, 15 type, key-operated levers forming a part of a universal keyboard and operatively connected to said type to move the same toward the platen and mounted upon said foldable support, a universal bar, ribbon mechanism, 20 and mechanism operatively connecting the universal bar and the ribbon mechanism, said mechanism having a part thereof foldable with said support and adapted to maintain its coöperative relation while said support is in its folded and unfolded positions.

25 8. In a visible typewriting machine, the combination of supporting means, a platen carriage movable along said supporting means, a foldable support movable relatively 30 to said supporting means, type, key-operated levers forming a part of a universal keyboard and operatively connected to said type to move the same toward the platen and mounted upon said foldable support, a universal bar adapted to be operated as the 35 keys are depressed, ribbon mechanism, and foldable mechanism operatively connecting the universal bar and the ribbon mechanism.

9. In a visible typewriting machine, the 40 combination of supporting means, a platen carriage movable along said supporting means, type, key-operated levers forming a part of a universal keyboard and operatively connected to said type to move the same toward the platen, a universal bar adapted to be moved when the keys are depressed, ribbon 45 vibrating mechanism, mechanism for imparting a lengthwise step-by-step movement to the ribbon, and a foldable non-separable operable connection between the 50 universal bar and the ribbon vibrating and feed mechanisms to adapt one part of the typewriter mechanism to be folded relatively to another to make the machine compact when not in use.

55 10. In a visible typewriting machine, the combination of supporting means, a platen carriage movable along said supporting means, a foldable support movable relatively 60 to said supporting means, type, key-operated levers forming a part of a universal keyboard and operatively connected to said type to move the same toward the platen and mounted with the type upon said fold-

able support, a universal bar adapted to be operated as the keys are depressed, ribbon mechanism for vibrating and feeding the ribbon, and a foldable non-separable operable connection between the universal bar and the ribbon mechanism to adapt one part 70 of said connection with the foldable support to be folded to place the keys of the keyboard in compact relation with the platen carriage and ribbon mechanism when not in use. 75

11. In a visible typewriting machine, the combination of supporting means, a platen carriage movable along said supporting means, a foldable support movable relatively to said supporting means, type, 80 key-operated levers forming a part of a universal keyboard and operatively connected to said type to move the same toward the platen and mounted upon said foldable support, a universal bar, ribbon mechanism, 85 and mechanism a part of which is mounted on the foldable support operatively connecting the universal bar and the ribbon mechanism, said mechanism having its operative relation maintained when the support is in its folded and unfolded positions. 90

12. In a visible typewriting machine, the combination of a platen carriage, a foldable support movable relatively to said platen carriage, type, key-operated levers forming 95 a part of a universal keyboard and operatively connected to said type to move the same toward the platen and mounted with the type upon said foldable support, a universal bar, ribbon mechanism, and a two-part non-separable foldable mechanism operatively connecting the universal bar and the ribbon mechanism, a part of said mechanism being mounted on said foldable support and foldable therewith toward the ribbon mechanism. 100

13. In a visible typewriting machine, the combination of supporting means, a platen carriage movable along said supporting means, ribbon mechanism for vibrating and 110 imparting a lengthwise feed to the ribbon, a foldable support, a universal bar mounted upon said support, key-operated levers forming a part of a universal keyboard mounted upon said foldable support, type-bars one 115 for each key-operated lever also mounted upon said support and adapted to operate the universal bar, and foldable and operative mechanism connecting the universal bar to the ribbon mechanism. 120

14. In a visible typewriting machine, the combination of supporting means, a platen carriage movable along said supporting means, a ribbon vibrator for moving a ribbon to and from the printing point, a foldable support, a universal bar mounted upon said support, key-operated levers forming a part of a universal keyboard mounted upon

said foldable support, type-bars one for each key-operated lever, and foldable operative mechanism connecting the universal bar to the vibrator, a part of said mechanism being mounted on said support.

15. In a visible typewriting machine, the combination of supporting means, a platen carriage movable along said supporting means, ribbon mechanism, a universal bar, 10 key-operated levers forming a part of a universal keyboard, type-bars one for each key-operated lever, and non-separable foldable operative mechanism connecting the universal bar to the ribbon mechanism.

16. In a visible typewriting machine, the combination of supporting means, a platen carriage movable along said supporting means, ribbon feed mechanism, a foldable support, a universal bar mounted upon said 20 support, key-operated levers forming a part of a universal keyboard mounted upon said foldable support and adapted to have the keys moved toward the platen carriage when not in use, type-bars one for each key-lever, 25 and foldable mechanism forming an operative connection between the universal bar and the ribbon feed mechanism.

17. In a typewriting machine, the combination of supporting means, a platen carriage adapted to move along said supporting means, a ribbon vibrator, a rod, a link operatively connecting the rod to the vibrator, a foldable support, key-operated levers mounted on the support, a universal bar also 30 mounted on the support and operatively connected to be moved when the key-operated levers are moved, and means operated by the universal bar adapted to operate said rod to vibrate the ribbon and maintain such 35 operative relation both in the folded and unfolded positions of the foldable support.

18. In a typewriting machine, the combination of supporting means, a platen carriage adapted to move along said supporting means, a ribbon vibrator, a rotary shaft 45 operatively connected to the vibrator, a foldable support, key-operated levers mounted on the support, a universal bar also mounted on the support and operatively connected to be moved when the key-operated levers are moved, and foldable means operated by the universal bar adapted to operate said shaft to vibrate the ribbon.

19. In a typewriting machine, the combination of supporting means, a platen carriage adapted to move along said supporting means, a ribbon vibrator, ribbon spools, a shaft operatively connected to move the vibrator and the spools, a foldable support, 50 key-operated levers mounted on the foldable support, a universal bar operatively connected to be moved when the key-operated levers are actuated, and means operated by the universal bar adapted to operate said shaft.

20. In a typewriting machine, the combination of supporting means, a platen carriage adapted to move along said supporting means, a ribbon vibrator, ribbon spools, a foldable support, key-operated levers 70 mounted on the support, a universal bar also mounted on the support and operatively connected to be moved when the key-operated levers are moved, and means operated by the universal bar adapted to operate both 75 vibrator and spools.

21. In a typewriting machine, the combination of a pivotally held ribbon-holder, a type aliner held to the ribbon-holder, a foldable support, a platen carriage, key-operated 80 levers mounted on said support, and means whereby the ribbon-holder may be operatively connected to the key-operated levers both in the folded and unfolded positions of the foldable support.

22. In a typewriting machine, the combination of a movable ribbon-holder, a type aliner held to the ribbon-holder, a foldable support, a platen carriage, key-operated levers mounted on said support, and means 90 including foldable and non-foldable parts whereby the ribbon-holder may be operatively connected to the key-operated levers.

23. In a typewriting machine, the combination of a movable ribbon-holder, a foldable support, a platen carriage, key-operated levers mounted on said support, and means including foldable parts whereby the ribbon-holder may be operatively connected to the key-operated levers both in the folded 100 and unfolded positions of the foldable support.

24. In a typewriting machine, the combination of a pivotally held ribbon-holder, a foldable support, a platen carriage, key-operated levers mounted on said support, and foldable means operatively connecting the key-operated levers to the ribbon-holder both in the folded and unfolded positions 105 of said support.

25. In a typewriting machine, the combination of a stationary support, a platen carriage adapted to move along said support, a ribbon-holder, a rod for moving said ribbon-holder, means operated by said rod 110 for feeding the ribbon lengthwise step-by-step in either direction, a foldable support, a key action mounted upon said support and adapted to fold therewith to make the machine compact when not in use and to place 115 the keys of the key action in close relation to the platen carriage, and means operatively connecting the key action to the rod.

26. In a typewriting machine, the combination of a stationary support, a platen carriage adapted to move along said support, a ribbon-holder, a shaft for moving said ribbon-holder, spools operated by said shaft for feeding the ribbon lengthwise step-by-step in either direction, a foldable support, 125 130

a key action mounted upon said support and adapted to fold therewith to make the machine compact when not in use and to place the keys of the key action in close relation to the platen, and means including a universal bar operatively connecting the key action to the shaft.

27. In a typewriting machine, the combination of a stationary support, a platen carriage adapted to move along said support, a pivotally held ribbon-holder, a shaft for moving said ribbon-holder, means operated by said shaft for feeding the ribbon lengthwise step-by-step in either direction, a foldable support, a key action mounted upon said support and adapted to fold therewith to make the machine compact when not in use and to place the keys of the key action in close relation to the platen, a universal bar operated on the depression of the keys, and foldable means operatively connecting the universal bar to the shaft.

28. In a typewriting machine, the combination of supporting means, a platen carriage adapted to travel along said supporting means, a vibratory ribbon-holder adapted to move the ribbon to cover and uncover the printing point, spools about which a ribbon may be passed, a shaft, means operated by said shaft for rotating said spools, means supported by the shaft to adapt a part of the operating means of the spools to be shifted from one to the other to adapt the ribbon to be moved in either direction, a foldable support, and key-operated means mounted upon said support and operatively connected to move said shaft in both the folded and unfolded positions of the foldable support.

29. In a typewriting machine, the combination of supporting means, a platen carriage adapted to travel along said supporting means, a vibratory ribbon-holder adapted to move the ribbon to cover and uncover the printing point, spools about which a ribbon may be passed, a shaft, means operated by said shaft for rotating said spools, a movable bar supported by the shaft to adapt a part of the operating means of the spools to be shifted from one to the other to adapt the ribbon to be moved in either direction, a foldable support, and key-operated means mounted upon said support and operatively connected to move said rod in both the folded and unfolded positions of the foldable support.

30. In a typewriting machine, the combination of a support, a carriage adapted to travel along said support, ribbon spools, a toothed member for rotating each spool, a shaft, arms mounted on said shaft, pawls carried by said arms adapted to engage the teeth of the toothed members, said arms being slidably held on said shaft, means connecting said arms to adapt the pawls to be

shifted along said shaft to cause one pawl to engage with its coöperating toothed member and the other pawl to be disengaged from its coöperating toothed member, and means for operating said shaft.

31. In a typewriting machine, the combination of a support, a carriage adapted to travel along said support, ribbon spools, a toothed member for rotating each spool, a shaft, arms mounted on said shaft, and adapted to be moved thereby, pawls carried by said arms adapted to engage the teeth of the toothed members, means connecting said arms to adapt the pawls to be shifted along said shaft to cause one pawl to engage with its coöperating toothed member and the other pawl to be disengaged from its coöperating toothed member, and foldable means for operating said shaft.

32. In a typewriting machine, the combination of a support, a carriage adapted to travel along said support, ribbon spools, a toothed member for rotating each spool, a shaft, arms mounted on said shaft, and adapted to be moved thereby, pawls carried by said arms adapted to engage the teeth of the toothed members, said arms being slidably held on said shaft, a bar connecting said arms to adapt the pawls to be shifted along said rod to cause one pawl to engage with its coöperating toothed member and the other pawl to be disengaged from its coöperating toothed member, means for holding the bar in its shifted position, and means for operating said shaft.

33. In a typewriting machine, the combination of a support, a carriage adapted to travel along said support, ribbon spools, a toothed member for rotating each spool, a shaft, arms mounted on said shaft, and adapted to be moved thereby, pawls carried by said arms adapted to engage the teeth of the toothed members, said arms being slidably held on said shaft, a bar having an engaging portion and connecting said arms to adapt the pawls to be shifted along said rod to cause one pawl to engage with its coöperating toothed member and the other pawl to be disengaged from its coöperating toothed member, said shaft having notches adapted to be engaged by the engaging portion of said bar to hold it in its adjusted position, and means for operating said shaft.

34. In a visible typewriting machine, the combination of a platen carriage, ribbon mechanism, key-operated levers forming a part of a universal keyboard, type-bars operatively connected to said key-operated levers, one for each lever, a universal bar foldable with a part of the machine relatively to the ribbon mechanism, and operative means arranged between the universal bar and the ribbon mechanism.

35. In a visible typewriting machine, the combination of supporting means, a platen

carriage movable along said supporting means, a ribbon vibrator, a shaft operatively connected to the vibrator, a bell-crank lever having one of its arms engaging a part of 5 said shaft to move the same and having its other arm slotted, a sliding cam member having a grooved portion engaged by said slotted end of the bell-crank lever, a spring normally forcing said member in one direction, 10 a rotary shaft extending transversely of the machine, a cam member held to said shaft and adapted to move the first-mentioned cam member against the tension of the spring to move the bell-crank lever and 15 operate the vibrator, arms projecting outward from said rotary shaft and provided with pins, a rod, arms having slotted ends held to said rod and engaging said pins, upwardly extending arms held to said rod, a 20 pivotally held universal bar adapted when moved to move said last-mentioned arms and thereby rotate the cam member carrying shaft, and key-operated levers operatively connected to move the universal bar when 25 depressed.

36. In a visible typewriting machine, the combination of a platen carriage, a ribbon vibrator, a lever operatively connected to move the vibrator, two relatively movable 30 cam members, one of which is adapted to move said lever, a universal bar, key-operated levers operatively connected to move the universal bar when depressed, and means operated by the universal bar to rotate one of said cam members.

37. In a visible typewriting machine, the combination of a platen carriage, ribbon mechanism, a bell-crank lever having one of its arms adapted to move the ribbon 40 mechanism and having its other arm slotted, a sliding cam member having a grooved portion engaged by said slotted end of the bell-crank lever; a spring normally forcing said cam member in one direction, a rotary shaft 45 extending transversely of the machine, a second cam member held to said shaft and adapted to move the first-mentioned cam member against the tension of the spring to move the bell-crank lever and operate the 50 ribbon mechanism, arms projecting outwardly from said rotary shaft, a rod, arms held to said rod and operatively connected to the arms of the rotary shaft, upwardly extending arms held to said rod, a pivotally 55 held universal bar adapted when moved to move said arms and thereby rotate the cam member carrying shaft, and key-operated levers operatively connected to move the universal bar.

60. 38. In a visible foldable typewriting machine, the combination of a platen carriage, ribbon mechanism, key-operated levers forming a part of a universal keyboard, a universal bar operatively connected to be

operated by said levers, and means for operating the ribbon mechanism, said means including a part rotatable with respect to another part to adapt the machine to be made compact when not in use.

39. In a typewriting machine, the combination of a platen carriage, ribbon mechanism, a movable cam member operatively connected to move said mechanism, a rotary shaft extending transversely of the machine, a cam member held to said shaft and 70 adapted to move the first-mentioned cam member, a universal bar, connections between the universal bar and the rotary shaft to rotate said shaft, and means for operating the universal bar.

40. In a visible typewriting machine, the combination of a platen carriage, a ribbon vibrator, a shaft for moving the vibrator, a bell-crank lever having one of its arms engaging a part of said shaft to move 85 the same and having its other arm slotted, a sliding cam member having a grooved portion engaged by said slotted end of the bell-crank lever, a spring normally forcing said member in one direction, a rotary shaft extending transversely of the machine, a cam member held to said shaft and adapted to move the first-mentioned cam member against the tension of the spring to move the bell-crank lever and operate the vibrator, a pivotally held universal bar operatively connected to rotate the cam member carrying shaft, and key-operated levers operatively connected to move the universal 90 bar when depressed.

41. In a visible typewriting machine, the combination of a platen carriage, ribbon mechanism, a rotary shaft extending transversely of the machine, means operated by said shaft for moving said mechanism, arms 105 projecting outwardly from said rotary shaft and provided with pins, a rod, arms having slotted ends held to said rod and engaging said pins, upwardly extending arms held to said rod, a universal bar adapted when 110 moved to move said last-mentioned arms and thereby rotate said shaft, and key-operated levers operatively connected to move the universal bar when depressed.

42. In a visible typewriting machine, the combination of a platen carriage, mechanism for giving a lengthwise step-by-step feed to a ribbon, a bell-crank lever having one of its arms operatively connected to move said mechanism, a sliding cam member adapted to operate said lever, a spring normally forcing said cam member in one direction, a shaft extending transversely of the machine, a cam member held to said shaft and adapted to move the first-mentioned cam member, a pivotally held universal bar, means movable by said universal bar to rotate the cam member carrying 120 125

shaft, and key-operated levers, operatively connected to move the universal bar when depressed.

43. In a visible typewriting machine, the combination of a platen carriage, ribbon mechanism including means for vibrating a ribbon and for giving it a lengthwise movement, a foldable support, a universal bar suspended on said support, key-operated levers forming a part of a universal keyboard mounted on said support, type-bars, one for each key-operated lever adapted to move the universal bar and operatively connected to the key-operated levers, arms idly engaging the universal bar and adapted to be moved thereby when the keys are depressed to operate the type-bars, a rotary shaft forming a pivotal means for said support, operative connections between the arms and said shaft, together with operative connections between the shaft and the ribbon mechanism and constructed to maintain cooperative relation between said shaft and said mechanism when said support is in its folded and in its unfolded positions.

44. In a visible typewriting machine, the combination of a platen carriage, ribbon mechanism for feeding a ribbon lengthwise, a foldable support, a universal bar suspended on said support, key-operated levers mounted on said support, type-bars, one for each key-operated lever, operatively connected to said levers, arms idly engaging the universal bar and adapted to be moved thereby when the keys are depressed to operate the type-bars, a rotary shaft forming a pivotal means for said support, operative connections between the arms and said shaft, together with operative connections between the shaft and the ribbon mechanism.

45. In a visible typewriting machine, the combination of a platen carriage, mechanism for vibrating a ribbon, a foldable support, a universal bar, key-operated levers mounted on said support, type-bars, one for each key-operated lever, operatively connected to said levers, arms moved by the universal bar, said bar being adapted to be moved when the keys are depressed to operate the type-bars, a rotary shaft forming a pivotal means for said support, operative connections between the arms and said shaft, together with operative connections between the shaft and the ribbon vibrating mechanism.

46. In a visible typewriting machine, the combination of a platen carriage, ribbon mechanism, a foldable support, a universal bar mounted on said support, key-operated levers forming a part of a universal keyboard and mounted on said support, type-bars, one for each key-operated lever adapted to move the universal bar and opera-

tively connected to the key-operated levers, 65 a rotary shaft forming a pivotal means for said support, operative connections between the universal bar and said shaft, together with operative connections between the shaft and the ribbon mechanism. 70

47. In a visible typewriting machine, the combination of a platen carriage, ribbon mechanism, a foldable support, a universal bar suspended on said support, key-operated levers, type-bars, one for each key-operated lever mounted on said support and operatively connected to the key-operated levers, a rotary shaft forming a pivotal means for said support, operative means between the universal bar and said shaft, together with 80 operative connections between the shaft and the ribbon mechanism.

48. In a visible typewriting machine, the combination of a platen carriage, ribbon mechanism for vibrating and feeding the 85 ribbon lengthwise, a foldable support, a universal bar mounted on said support, key-operated levers forming a part of a universal keyboard mounted on said support, type-bars, one for each key-operated lever, 90 operatively connected to the key-operated levers, and foldable mechanism forming a connection between the universal bar and the ribbon mechanism, the point of folding of said mechanism corresponding to the 95 point of folding of said support.

49. In a typewriting machine, the combination of a frame, a platen carriage supported in the frame, ribbon mechanism fixed to the frame adapted to move the ribbon lengthwise and to vibrate the ribbon to cover and uncover the printing point, a foldable support connected with the frame, key-operated levers mounted on said support and foldable therewith, a universal bar 105 mounted on the foldable support, type bars operatively connected with the key levers and adapted to actuate the universal bar, and means connecting the universal bar and ribbon mechanism for actuating the ribbon 110 mechanism, said means maintaining an operative connection between the universal bar and the ribbon mechanism at all times.

50. In a typewriting machine, the combination of a frame, a platen carriage supported in the frame, ribbon mechanism fixed to the frame adapted to move the ribbon lengthwise and to vibrate the ribbon to cover and uncover the printing point, a 120 foldable support connected with the frame, key-operated levers mounted on said support, a universal bar mounted on said support, type bars mounted on said support operatively connected with the key levers 125 and adapted to actuate the universal bar when the key levers are operated, and means connecting the universal bar and ribbon

- mechanism for actuating the ribbon mechanism, said means maintaining an operative connection between the universal bar and the ribbon mechanism at all times.
5. In a typewriting machine, the combination of a frame, a platen carriage supported in the frame, means supported on the frame for moving a ribbon lengthwise step-by-step past the printing point, a foldable support connected with the frame, key-operated levers mounted on the support, type bars operatively connected with the key levers and mounted on said support, a universal bar mounted on the support and actuated by said type bars, and means connecting the universal bar and ribbon-moving means for actuating the ribbon-moving means and adapted to maintain an operative connection between the universal bar and ribbon-moving means at all times.
10. In a typewriting machine, the combination of a frame, a platen carriage supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 70 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
15. In a typewriting machine, the combination of a frame, a platen carriage supported on the frame, a ribbon vibrator supported on the frame for moving a ribbon to and from the printing point, a foldable support connected with the frame, key-operated levers mounted on the support, type bars operatively connected with the key levers and mounted on said support, a universal bar mounted on the support and actuated by said type bars, and means connecting said bar and ribbon vibrator for actuating the vibrator, said means maintaining an operative connection between the universal bar and ribbon vibrator at all times.
20. In a typewriting machine, the combination of a frame, a platen carriage mounted in the frame, a ribbon vibrator, ribbon spools, a rock shaft operatively connected to move the vibrator and the spools, a foldable support connected with the frame, key-operated levers mounted on the foldable support, a universal bar operatively connected to be moved when the key-operated levers are actuated, and means operated by the universal bar adapted to rock said shaft.
25. In a typewriting machine, the combination of a frame, a platen carriage movable in said frame, ribbon mechanism mounted on said frame for vibrating a ribbon to cover and uncover the printing point and for feeding the ribbon lengthwise step-by-step, a rock shaft for actuating said ribbon mechanism, a lever operatively connected to rock said shaft, a rotatable shaft extending transversely of the machine and supported in said frame, a cam fixed on said rotatable shaft, a co-operating cam slidably mounted on said rotatable shaft and adapted to actuate said lever, a universal bar, key-operated levers operatively connected to move the universal bar, a support for the universal bar and key levers loosely pivoted 30 on said rotatable shaft and adapted to swing about said shaft to enable the support and frame to be folded relatively to each other, and means operated by the universal bar to actuate the rotatable shaft and rotate said fixed cam.
35. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 75 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
40. In a typewriting machine, the combination of a frame, a vibratory ribbon holder supported on the frame, ribbon spools supported on the frame, a rotatable shaft journaled in the frame transversely of the machine, key-operated levers, a universal bar 90 adapted to be actuated when said key levers are operated, a foldable support for the key levers and universal bar loosely pivoted on said shaft, means actuated by the universal bar for rotating said shaft, said means maintaining an operative connection at all times, and means operated by said shaft for actuating the ribbon holder and ribbon spools, said means maintaining an operative connection between said rotatable shaft and 95 the ribbon holder and spools at all times.
45. In a typewriting machine, the combination of a frame, a vibratory ribbon holder for moving a ribbon to cover and uncover the printing point mounted on said frame, a rotatable shaft journaled in the frame transversely of the machine, key-operated levers, a universal bar operatively connected to be moved when said key levers are actuated, a foldable support for the key levers and universal bar loosely pivoted on said shaft, means actuated by the universal bar for rotating said shaft, said means maintaining an operative connection at all times, and means operated by said shaft for vibrating the ribbon holder, said means maintaining an operative connection between said rotatable shaft and ribbon holder at all times.
50. In a typewriting machine, the combination of a frame, ribbon mechanism for feeding a ribbon lengthwise mounted on said frame, a rotatable shaft journaled in the frame transversely of the machine, key-operated levers, a universal bar operatively 100
55. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 105 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
60. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 110 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
65. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 115 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
70. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 120 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
75. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 125 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.
80. In a typewriting machine, the combination of a frame, a vibratory ribbon holder supported on the frame, ribbon spools supported on said frame, a rock shaft supported on the frame for operating said ribbon holder and spools, a foldable support, a universal bar mounted on said support, key-operated levers mounted on said support and operatively connected to move the universal bar, a rotatable shaft journaled in the frame, 130 said support being loosely pivoted on said rotatable shaft, arms fixed to said rotatable shaft, means connecting said arms with the universal bar to operate said rotatable shaft, and means operatively connecting said rotatable shaft and said rock shaft to actuate the ribbon mechanism, said means maintaining an operative connection between said shafts at all times.

connected to be moved when said key levers are actuated, a foldable support for the key levers and universal bar loosely pivoted on said shaft, means actuated by the universal 5 bar for rotating said shaft, said means maintaining a constant operative connection between the bar and shaft, and means operated by said shaft for actuating the ribbon

feeding mechanism, said means maintaining a constant operative connection between said 10 rotatable shaft and ribbon feeding mechanism.

This specification signed this 13th day of Dec., A. D. 1915.

CHARLES PHILO MOSHER
